UNITED STATES PATENT OFFICE.

HORACE G. HARPER, OF DETROIT, MICHIGAN.

REGISTER.

1,068,238.

Specification of Letters Patent. Patented July 22, 1913.

Application filed January 26, 1912. Serial No. 673,514.

To all whom it may concern:

Be it known that I, HORACE G. HARPER, a citizen of the United States of America, residing at Detroit, in the county of Wayne 5 and State of Michigan, have invented certain new and useful Improvements in Registers, of which the following is a specification, reference being had therein to the accompanying drawings.

10 This invention relates to improvements in registers and more particularly to registers employing a strip of paper upon which the items are recorded and which is mounted upon rolls.

15 The object of the invention is to provide a simple and convenient index for such registers, to provide means for taking care of the expansion and contraction of the paper and prevent wearing and tearing of the 20 edges, and to provide certain other new and useful features, the invention consisting in the matters hereinafter more fully set forth and pointed out in the claims, reference being had to the accompanying drawings, in 25 which:—

Figure 1 is a plan view of a device embodying the invention with parts broken away to show the construction; Fig. 2 is a longitudinal vertical section through the 30 same; Fig. 3 is a transverse section on the line $x-x$ of Fig. 1 of a portion of the casing; and Fig. 4 is a perspective detail of a portion of the record tape or strip and driving rolls.

35 As shown in the drawings, 1 is a casing of any suitable form or construction having a flat top or cover 2 provided with an opening 3 to display and expose a portion of the record strip 4 which travels beneath the 40 opening and upon which entries may be made through said opening. A writing bed or table 5 extends beneath the opening to support the strip as it travels from a winding roll 6 at one end of the casing to a winding roll 7 at the other end of the casing, 45 said rolls being suitably journaled in bearings upon brackets 8 mounted upon the bottom of the casing. From the roll 6 the paper travels upward over an idler roll 9 journaled in the upper end of the bracket, and then over the table 5 to a second idler roll 10 journaled in bearings on the upper 50 end of the other bracket.

To actuate the winding rolls and wind the 55 paper from one to the other in either direction, at the same time keeping a tension

upon the strip so that it will lie flat and smooth upon the table, a friction driving roll 11 is mounted in suitable slotted bearings 12 on the bracket 8 opposite the roll 9 60 and a similar friction roll 13 is mounted in a like manner opposite the idler 10. Swinging arms 14 are carried by the shafts of the friction rolls 11 and 13 and these arms are provided with bearings at their lower ends 65 for friction rolls 15 and 16 of the same diameter and form as the rolls 11 and 13, the rolls 15 and 16 being adapted to engage the paper which is wound upon the rolls 6 and 7 respectively. Secured to one end of the 70 shafts of the rolls 11 and 13 are pulleys 17 and similar pulleys 18 are secured to one end of the shafts of the rolls 15 and 16. An endless belt 19 engages all four of the pulleys and the run of said belt between the 75 pulleys 18 is engaged by a large driving pulley 20 mounted centrally within the casing and having a shaft 21 extending through the side thereof to which a suitable crank 22 may be attached for turning the driving 80 pulley and actuating the driving rolls.

The pair of friction rolls 11 and 15 is held in contact with the adjacent idler 9 and roll of paper mounted upon the winding roll 6, by means of a coiled spring 23 which is connected at one end to the arm 14 and at its opposite end to the adjacent bracket 8, thus exerting a pull upon the arm to move the roll 11 into frictional contact with the recording strip which passes upward between 90 it and the idler 9. This spring also serves to hold the friction roll 15 in frictional engagement with the recording strip which is wound upon the roll 6. In a similar manner, a like spring holds the friction rolls 13 95 and 16 in frictional contact with the recording strip.

When the driving pulley 20 is turned in either direction the record strip 4 will be positively driven by means of the friction 100 rolls 11 and 13 and thus the strip will be held tight and smooth in its run between said rolls over the table 5. The friction rolls 15 and 16 are at the same time positively driven by the belt 19 and being held 105 in frictional engagement with the record strip which is wound upon the winding rolls, will drive said rolls positively and at the desired speed to wind the strip thereon at the same rate that it is driven by the 110 friction rolls above. As the strip is wound from one winding roll to the other and the

roll of paper increases in diameter upon one of the rolls and decreases in diameter upon the other, the arms 14 will swing accordingly and provide for such variation in the diameter of the rolls.

5 Obviously, the driving pulley 20 may be turned by the crank 22 as shown or in any other suitable manner.

To provide a suitable index by means of 10 which any item or account entered upon the record strip may be readily found, an index line 24 is drawn upon the face of the record strip from one end to the other thereof and diagonally across said strip. In the 15 casing cover 2 adjacent to the opening 3 is a second opening 25 beneath which an extension 26 of the table 5 extends to support the record strip beneath said opening. The several items or accounts entered upon 20 the record strip may bear index markings or numbers as indicated at 27 and an indicator plate 28 is provided with similar indicator markings or numbers placed opposite graduations 29 which extend to the 25 edges of a slot 30 in said plate through which slot the inclined or diagonal index line 24 on the record strip may be seen.

As the record strip is wound from one winding roll to the other, the index line 24 30 as seen through the slot 30 in the indicator plate, will travel along said slot owing to its diagonal position upon the strip. When said index line registers with one of the 35 graduations 29 the particular item or account bearing the index marking 27 which corresponds to the like index mark opposite 40 said graduation will show through the opening 3. The operator therefore runs the record strip along until the index line registers with the index to the particular item or account that he desires and thus a very simple and convenient index mechanism is provided for the record strip.

The indicator plate 28 is held in position 45 beneath the opening 25 by means of screws 31 engaging longitudinal slots 32 at the ends of the plate and guide ribs or tongues 33 on the plate project downward therefrom in engagement with each edge of 50 the record strip so that should there be any lateral movement of the strip as it travels past the plate, said plate, by the engagement of the ribs 33 with its edges, will move laterally with it and thus maintain the accurate 55 relation of the index line 24 to the graduations on the plate. Obviously the said indicator plate may be otherwise held against movement with the travel of the record strip and so that it will freely move laterally with the strip, any suitable means 60 being provided for accomplishing this purpose and maintaining the relation of the plate and strip.

Changes in the condition of the atmosphere 65 will cause the paper record strip to

expand and contract, materially, changing its length and causing it to wrinkle. This expansion or contraction may not be the same along each edge of the strip and it would cause an uneven winding of the strip 70 upon the rolls. Undue expansion or contraction would also change the position of the index line relatively to the graduation on the indicator plate and thus said line would not correctly perform its function. To prevent any uneven expansion or contraction and to hold the edges of the record strip smooth and straight, a strip or tape 34 75 preferably of fabric or other material which is not greatly affected by changes of temperature is glued along each edge of the record strip upon the lower or inner side thereof. These strips or tapes take the strain of driving the record strip, giving the paper strength and preventing its being 80 worn or torn along its edges. These tapes also hold the edges straight and smooth so that the wrinkling of the paper will not affect the accurate even winding of the record strip. 85

Obviously, the index mark on the paper may be a continuous unbroken straight line, as shown or it may be an irregular or broken line, and other changes in the construction and arrangement of the parts may be made without departing from the spirit 90 of my invention. I do not therefore limit myself to the particular form or construction shown. 95

What I claim as my invention is:—

1. An autographic register having in combination a record strip provided with a diagonal index line extending longitudinally thereof, means for causing longitudinal travel of said record strip, a member supported adjacent to said strip having indicia to indicate pre-determined portions of said strip and so placed with respect to said diagonal line that when said line intersects the line of arrangement of said indicia and coincides with an index thereof, that portion of the record strip to which said index refers will be in a pre-determined position. 105

2. An autographic register having in combination winding rolls, a record strip adapted to be wound from one to the other of said rolls, said strip being provided with an index line extending diagonally across the same throughout its length, and a member 110 provided with indicia referring to pre-determined portions of said strip arranged transversely of said diagonal line and strip to indicate by the coincidence of said lines and one of the indicia, that the portion of 115 the strip indicated by said index is in a pre-determined position.

3. An autographic register having in combination a record strip provided with index 120 means arranged diagonally of said strip 125

longitudinally from end to end thereof to index pre-determined portions of said strip, means for actuating the strip longitudinally, and a member provided with indicia arranged transversely of said strip and so placed with respect to said diagonal arrangement of said indexing means that when, during the travel of said strip, said indexing means comes into coincidence with an index on said member, that portion of the strip which is indicated by said index will be in a pre-determined position.

4. An autographic register having in combination a record strip provided with indexing means having an angular arrangement transversely of said strip for each record thereon, means for actuating said strip longitudinally, and an indicator supported adjacent to the surface of said strip transversely to the line of travel thereof and having indicia for the several records adapted to coincide with the indexing means on the strip when said strip is caused to travel longitudinally and indicate by such coincidence that the particular record indicated by the index in coincidence with said indexing means, is in a predetermined position.

5. An autographic register having in combination a casing provided with an opening, rolls in said casing, means for turning the rolls, a record strip actuated by said rolls to travel past said opening, said strip being provided with indexing means for each record thereon arranged angularly to the line of travel of said strip, an indicator for the several records arranged transversely to the line of travel of said strip and indexing means thereon, to coöperate with said indexing means during the travel of said strip past said opening and indicate the particular record exposed to view.

6. In an autographic register having in combination a casing provided with an opening therein, rolls in said casing, means for turning said rolls, a record strip actuated by said rolls to travel past said opening, said strip being provided with a diagonal index line extending longitudinally thereof and across said opening, and a series of indicia to correspond with records on said strip and arranged along said opening transversely of said strip.

7. In an autographic register having in combination rolls, means for actuating said rolls, a record strip moved longitudinally by said rolls and having a diagonal line thereon extending from end to end thereof, and an indicator member supported adjacent to the surface and transversely of the line of travel of said strip and having an opening extending transversely of said line and strip with indicia so placed with respect to said diagonal line that when said line intersects a certain index on said mem-

ber, the particular record indicated by said index is exposed to view.

8. In a device of the character described, the combination of rolls, a record strip engaged and actuated by said rolls and having an index mark, and an indicator plate extending transversely of and free to move laterally with said strip and provided with marks to register with said index mark.

9. In a device of the character described, the combination with a casing having an opening, rolls in said casing, and means for actuating the rolls, of an index strip engaged and moved by said rolls opposite said opening and provided with an index line, an indicator plate supported adjacent to said strip opposite said opening against movement with the strip longitudinally thereof and free to move laterally with said strip, said plate being formed with a slot extending transversely of said strip and marks along the edge of said slot to register with said index line as said line travels along said slot during the movement of the strip and indicate by such registry the position of records on said strip.

10. An autographic register having in combination a casing having an opening and rolls in said casing, means for actuating said rolls, a paper record strip engaged by said rolls and provided with a diagonal index line extending from end to end thereof, an indicator having marks to register with said line during the travel of said strip to indicate by such registry the position of records on said strip, and a fabric strip secured to each edge of the record strip throughout its length.

11. In a device of the character described, the combination of a casing having an opening in its top, winding rolls in said casing, a record strip adapted to be wound from one to the other of said rolls, idlers journaled near the casing top over which idlers the strip passes, friction rolls opposing the idlers, means for yieldingly holding said friction rolls toward the idlers to clamp the record strip between them, means for turning the winding rolls, and means for positively actuating the friction rolls.

12. In a device of the character described, the combination of a casing having an opening in its top, winding rolls in said casing, a record strip to be wound from one of said rolls to the other, idler rolls to guide the strip adjacent to said opening, friction rolls opposite the idlers, friction rolls opposite the winding rolls, means for supporting the last named friction rolls to swing toward the winding rolls, and means for driving all of the friction rolls.

13. In a device of the character described, the combination of a casing having an opening in its top, winding rolls in said casing, a record strip adapted to be wound from one

to the other of said rolls, idlers near the top of the casing over which said record strip extends, movably supported friction rolls opposite said idlers, swinging arms 5 having bearings at their lower ends, friction rolls mounted in said bearings on said arms to swing into contact with the record strip on the winding rolls, means for yieldingly holding the friction rolls in frictional 10 contact with the record strip wound on

said winding rolls and passing over said idlers, and means for turning all of said friction rolls.

In testimony whereof I affix my signature in presence of two witnesses.

HORACE G. HARPER.
